UNITED STATES PATENT OFFICE.

WILLIAM D. ROOT, OF CLEVELAND, OHIO, ASSIGNOR TO THE MACHINERY IMPROVEMENT COMPANY, OF CLEVELAND, OHIO, A CORPORATION OF OHIO.

CORN-POPPING MACHINE.

Application filed June 13, 1923. Serial No. 645,064.

To all whom it may concern:

Be it known that I, WILLIAM D. Root, a citizen of the United States, residing at Cleveland, in the county of Cuyahoga and 5 State of Ohio, have invented a certain new and useful Improvement in Corn-Popping Machines, of which the following is a full, clear, and exact description.

This invention relates to popping machines of the type in which there is a continually driven popping device which has a definite cycle of operations for popping and delivering each charge of corn, which has means for automatically supplying a charge of unpopped corn at the beginning of each cycle of operations and which when once started in operation continues to pop one charge after the other until the driving mechanism is stopped.

10 An object of the present invention is to provide means for controlling the operation of the popping machine which includes a manually operable controller movable to on and off positions to start or stop the machine, together with means operable when the controller is moved to off position to continue the operation of the machine until the cycle of operation is completed and the charge in the popping device has been popped and 15 then to stop the machine.

20 A further object is to provide timing means for controlling the discharging and feeding means to provide a shorter or longer time for the popping of the charge of corn.

25 A further object is to provide means for rendering the heating device inoperative during the interval between successive popping operation while the unpopped corn is being discharged from the popping device and a fresh charge of unpopped corn is being delivered thereto.

30 A further object is to provide means continually operated from the driving means for controlling the operation of the charge feeding popper discharging and popper heating devices.

35 Other objects will be apparent from the following description and accompanying drawings.

40 The following description and accompanying drawings set forth in detail certain means embodying the invention, the disclosed means, however, constituting but one of the various mechanical forms in which

the principle of the invention may be employed.

Reference should be had to the accompanying drawings forming a part of this specification in which Fig. 1 is a side elevation of the popping machine; Fig. 2 is a top plan view of the machine; Fig. 3 is a rear elevation of the machine; Fig. 4 is a side elevation of the popping cylinder; Fig. 5 is a section on line 5—5 of Fig. 4; Fig. 6 is a fragmentary detail view of the controller 45 operated from the driving mechanism; Fig. 7 is a fragmentary sectional view showing the device for discharging unpopped corn from the popping cylinder; Fig. 8 is a side elevation of the gate for controlling the discharge of unpopped corn; Fig. 9 is a wiring diagram showing the motor and heater circuits.

50 Referring to the accompanying drawings, the popping machine herein disclosed and embodying the present invention consists of a continuously driven popping device which is adapted to receive charges of unpopped corn and has a definite cycle of operations during which the corn is popped, the popped corn is separated from the unpopped corn and the corn which will not pop is finally discharged separately from the popped corn; a device which operates to automatically feed the unpopped corn to the popping device at the beginning of each operation thereof; and a driving and controlling mechanism by means of which the popping device is continuously driven and the devices for feeding a charge of unpopped corn to the popping device and discharging unpopped corn therefrom are operated at predetermined intervals.

Popping device.

55 The popping device is in the form of a rotatably mounted cylinder 1 which is provided with side plates 2 and 3 on the outer and inner sides thereof, the side plate 2 having an axial opening 4 through which unpopped corn is delivered to the cylinder and the inner side plate 3 having a discharge outlet 5 for popped corn between the axis and periphery thereof. The cylinder 1 is carried by a horizontal shaft 6 which extends through the axial opening 4 of the outer side plate 2 and is attached to a plate 7 which is rigidly secured to the side plate 2.

and is offset inwardly therefrom opposite the opening 4. The cylindrical wall of the cylinder 1 is in the form of a screen 8, the mesh of which is fine enough to retain the 5 kernels of unpopped corn. An inner spiral screen 9 is attached to its outer end to the screen 8 and at its inner end to a side wall of the discharge chute 10 which delivers the popped corn through the discharge 10 opening 5 in the inner wall 3 of the cylinder. The spiral screen 9 is of coarser mesh than the screen 8 and will permit the unpopped kernels to pass readily therethrough but will retain the popped corn. The inner screen 9 15 serves to separate the popped corn from the unpopped corn during each revolution of the cylinder and delivers the popped corn to the discharge chute 10 so that the popped corn is delivered from the cylinder during 20 the popping. An electric heater 11 (see Figs. 1 and 3) is located adjacent the underside of the cylinder directly beneath the portion of the cylinder where the unpopped corn is supported during the rotation of the 25 cylinder.

As viewed in Figs. 1 and 4, the cylinder rotates in a clockwise direction. The unpopped corn tends to move with the cylinder but is continuously rolling back toward 30 the central bottom portion thereof. For this reason the unpopped corn will be supported in a position slightly at one side of the central transverse plane of the cylinder and the heater 11 is located to the left of the 35 central transverse plane of the cylinder. The cylinder in its rotation continuously agitates the corn and retains it directly over the heater. The unpopped corn is delivered to the cylinder through a chute 12 which extends into the opening 4 in the outer side plate 3 and discharges against the inner plate 7. The plate 7 serves as a partition between the inlet chute for unpopped corn and the discharge chute for the popped corn. 40

45 After the cylinder has operated for a sufficient time to pop all the corn of a charge which will pop, the unpopped corn remaining in the cylinder is discharged therefrom by means of a discharge gate 13 which is 50 mounted within the cylinder a short distance in advance of the point where the spiral screen 9 is attached to the outer screen 8. The gate 13 is fixed to a horizontal shaft 14 which extends through the cylinder and is 55 journaled in the side walls 2 and 3 thereof. The gate 13 is a box-like member which has a flat bottom plate 15 which has its inner edge adjacent the shaft 14 and an outer free edge which is adapted when the gate is moved to 60 discharge position to engage the outer screen 8 of the cylinder and deflect any material within the cylinder inwardly. The gate 13 has a top wall 16 spaced inwardly from the bottom wall 15 and the top wall 16 has an 65 outturned flange 17 at its forward end, the

edge of which forms with the outer edge of the bottom plate 15, a narrow slot 18, which will permit unpopped kernels of corn to pass into the gate but will prevent the entry of popped kernels. The gate 13 has a rear 70 laterally inclined wall 19 which during the rotation of the cylinder serves to deflect the unpopped corn which has entered the gate through a discharge opening 20 in the side plate 2 into a discharge chute 21 fixed to the 75 outer side of a cylinder. An arm 22 is fixed to the shaft 14 intermediate its ends on the outer side of the side plate 2, the outer end of the arm 22 is provided with an outwardly projecting pin by means of which it is 80 actuated by a curved actuating lever 24 which is pivoted to the side plate 2 by means of a pivot 25 intermediate its ends. When the outer end of the actuating lever 24 is swung inwardly, the gate 13 is swung outwardly to discharging position. A rod 26 is pivoted to the inner end of the actuating arm 22 and has its outer end slidably mounted in an opening in a bracket 27 carried by the side plate 2. A compression 85 coil spring 28 is interposed between a collar 29 fixed to the rod 26 and the bracket 27. The rod 26 forms with the inner end of the arm 22, a spring toggle which moves past dead center as the discharge gate 13 moves 90 outwardly to discharging position and serves to yieldingly retain the discharge gate 13 either in a position to scoop up the unpopped corn or in a position to discharge the 95 corn which has accumulated within the gate 13 into the discharge chute 21. The inner end of the curved lever 24 is provided with an outwardly projecting portion 30 which is adapted to engage with a suitable trip which is operated by the driving mechanism to 100 move the gate 13 to discharging position. The inner end portion of the lever 24 lies close to the side plate 2 while the outer end portion which overlies the actuating arm 22 is offset outwardly from the side plate 2. 105 The outer end portion of the lever 24 has an inclined lug 31 on the inner side thereof which engages with a fixed trip after the lever 24 has been actuated to shift the discharge gate into engagement with the screen 110 to shift the lever 24 to its original position and to shift the gate 13 to its normal position out of engagement with the screen 8. The lugs 30 and 31 are spaced nearly 180° apart 115 and are so positioned that the lugs 30 will 120 be engaged by the fixed trip after the gate 13 has passed the heater so that as the gate is moving above the axis of the cylinder the unpopped corn therein will be discharged 125 through the discharge chute 21.

Feeding device for unpopped corn.

A supply of unpopped corn is maintained within a hopper bottom receptacle 32 which is supported upon the top wall 33 of the cas- 130

ing within which the popping mechanism is enclosed. The receptacle 32 has a cylindrical discharge portion 34 which fits within a circular opening in the top wall 33 and is supported by means of lugs 35 formed on the hopper bottom thereof which rest upon the top of the wall 33 adjacent the opening. The receptacle 32 is thus adapted to be removed bodily from the casing. The lower end of the discharge portion 34 of the receptacle 32 extends into the open upper end of an inclined tubular chute 36 which is supported at its outer end by means of brackets 37 rigidly attached to the enlarged upper end 38 of the chute 12 which delivers to the cylinder 1 and at its inner end is supported by means of bolts 37^a extending from the top wall 33. The delivery of unpopped corn from the chute 36 to the open upper end 38 of the chute 12 is controlled by means of a valve 39 which is fixed to a horizontal pivot pin 40 journaled to the side walls of the upper end portion 38 of the chute 12. The valve 39 has a bottom 41 which extends from the pivot pin 40 and side walls 42 which form continuations of the side walls of the tubular chute 36. Extending upwardly from the bottom 41 there is a curved cut-off plate 43 which serves to close the discharge end of the chute 36 when the valve 39 is operated to deliver a charge of corn to the chute 12. The valve 39 normally occupies the position shown in Fig. 3 of the drawing in which the valve is in communication with the chute 36 and the cut-off plate 43 and bottom plate 41 form a pocket adapted to retain a predetermined charge of corn, the pivot 40 being at a sufficient height to prevent overflow of corn from the chute 36 into the chute 12. The valve 39 is operated by means of a lever 44 which is pivoted at its outer end to an outwardly projecting bracket carried by the upper end portion 38 of the chute 12. The lever 44 has a slot 46 at its inner end which receives a pin 47 which projects from one of the side walls 42 of the valve. The valve 39 is operated at predetermined intervals to deliver a charge of corn to the chute 12 by means of a vertically disposed rod 48 which is pivoted to the lever 44 intermediate its ends, the rod 48 being actuated at predetermined intervals, as will be hereinafter explained, from the driving mechanism.

Driving and controlling mechanism.

During the operation of the machine the cylinder 1 is continuously driven by means of an electric motor 49 which drives the shaft 6 through a worm 50 on the motor shaft, a worm gear 51 on a horizontal counter-shaft 52 which carries a small gear 53 which meshes with a large gear 54 fixed to the shaft 6. The shafts 6 and 52 are journaled in a rectangular frame 55 which is supported upon the base which carries

the motor 49 and which encloses the gearing mounted on said shafts. Toward the rear end of the frame 55 there is a horizontal shaft 56 to which is fixed a ratchet wheel 57 and a controller disc 58. Intermittent rotative movement is imparted to the shaft 56 through a lever 59, which is pivoted on the shaft 56 between the ratchet wheel 57 and disc 58. The forward end of the lever 59 extends along the inner side of the gear 54 above the shaft 6 and is engaged during each revolution of the gear 54 by a roller 60 carried on the inner side of the gear. At its rear end the lever 59 carries a pawl 61 which engages with the teeth of the ratchet wheel 57. During each rotation of the gear 54 the forward end of the lever 59 is engaged by the roller 60 and swung upwardly about its pivot causing the rear end thereof which carries the pawl 61 to swing downwardly and turn the ratchet wheel 57 through a partial revolution. The ratchet wheel 57 is also engaged by a second pawl 62 mounted on a fixed pivot which serves to prevent reverse rotation of the ratchet wheel. The ratchet wheel 57 and disk 58 control the operation of the devices for feeding a charge of unpopped corn to the cylinder and discharging the unpopped corn from the cylinder after the popping period. Since it is desirable to vary the time of the popping operation, means are provided for varying the throw of the lever 59. To this end, an adjustable stop 63, carried by the bracket 64 mounted on the rear end of the frame 55, engages with the rear end of the lever 59 and limits the upward movement thereof. The stop member 63 is in the form of a vertically disposed pin slidably mounted in the bracket 64, the lower end of the pin 63 being in the path of movement of the lever 59 and the upper end thereof having a head which is engageable with any one of a series of notches in the edge of a bar 64^a pivoted on the bracket 64 and held in engagement with the head of the pin 63 by means of a leaf spring 64^b. The stop 63 serves to hold the forward end of the lever 59 when the same is not engaged by the roller 60 at varying heights above the shaft 6. The extent of movement of the lever 59 can thus be regulated and, as the lever 59 is adjusted for greater or less angular movement, the ratchet wheel 57 will be turned through a greater or smaller angle upon each actuation of the lever 59. Since the ratchet wheel 57 and controller disc 58 effect actuation of the feeding, discharging and heating devices once during each revolution, it is obvious that by adjusting the stop 63 the time required to complete a cycle of operations may be lengthened or shortened. The valve operating rod 48 is actuated through a U-shaped bar 65 which is positioned upon the outer side of the ratchet wheel 57 and is se-

cured at its ends to the rod 48. The upper leg of the U-shaped bar 65 is engaged upon each complete revolution of the ratchet wheel 57 by a roller 66 upon the outer side 5 of the ratchet wheel. The roller 66 lifts the operating rod 48 and swings the valve 39 to a position to discharge its contents into the chute. When the roller 66 moves out of engagement with the upper leg of the U- 10 shaped bar 65 the valve 39 drops by gravity to charge receiving position. If for any reason the valve 39 should not move by gravity to its lowermost position the roller 66 as it passes beneath the shaft 56 will en- 15 gage with the lower leg of the U-shaped bar 65 and shift the rod 48 downwardly until the valve 39 is in its lowermost position where it will receive a full charge of corn from the chute 36.

20 A slidably mounted rod 67 extends horizontally through the rectangular frame 55 immediately in front of the ratchet wheel 57. The rod 67 carries a conical disk 68 which overlies the inner side of the ratchet wheel 57 and is provided with a collar 69 on the inner side of the frame 55 and a roller 70 between the collar 69 and the cylinder 1. The collar 69 is engaged by a leaf spring 71 carried by the frame 55 which serves to 25 yieldingly hold the collar 69 against the frame 55. The conical disk 68 is engaged upon each revolution of the ratchet wheel 57 by a cam lug 72 upon the inner face of the wheel. When the lug 72 is in engagement 30 with the disk 68 the roller 70 is forced inwardly toward the side plate 2 of the cylinder and is in the path of the lug 30 on the inner end of the actuating lever 24. The engagement of the lever 24 with the roller 70 35 causes the discharge gate 13 to be moved to the discharging position. The cam lug 72 is so positioned with respect to the actuating roller 66 that the gate 13 is actuated and returned to normal position just prior to the 40 engagement of the roller 66 with the bar 65 to actuate the charge feeding device. A fixed roller 73 is mounted on the inner side of the frame 55 and projects toward the cylinder 1 a less distance than the roller 70 45 and is in the path of the lug 31 upon the outer end of the actuating lever 24 when said lever has been actuated to move the gate 13 to discharging position and serves to return the gate 13 to normal position after it 50 has gathered up the unpopped kernels of corn from the screen 8.

The controller disk 58 consists of a body portion 74 made of insulating material and a metallic cover plate 75 which covers the outer face of the disk and has a peripheral flange 76 which overlies the periphery thereof. The disk 58 is engaged by three spring contact strips 77, 78 and 79, the contact 77 engaging the periphery of the disk, the contact 78 engaging the cover plate 75 adjacent

its periphery and the contact 79 engaging the plate 75 nearer the axis of rotation. The peripheral flange 76 of the cover plate has a gap 80 therein so that during a portion of each revolution the contact strip 77 is in engagement with the insulating body 74 of the disk. Adjacent the ends of the gap 80, notches 81 and 82 are formed in the periphery of the insulating body 74, the notch 81 being at the forward end of the gap 80 and 75 the notch 82 at the rear end thereof. The flange 76 terminates at the forward edge of the notch 81 and the forward wall of the notch 81 is substantially radial so that when the spring contact strip 77 rides off the end 80 of the flange 76, it will snap into the notch 81 immediately breaking the circuit through the plate 75 so that there is no danger of forming an arc between the contact strip and plate which would burn the contact 85 as the circuit is being broken. The rear wall of the notch 82 is inclined and the forward wall thereof is substantially radial so that the contact strip 77 snaps into the notch 82 when the notch is moved beneath the contact 90 strip. The flange 76 extends down into the notch 82 so that when the contact strip 77 snaps into the notch, the circuit through the contact strip is instantly reestablished. This construction prevents arcing between the 95 strip 77 and the flange 76 when contact is made between them. The front radial wall of the notch 72 also forms a stop against which the forward end of the strip 77 will engage to prevent any back lash of the disk 100 which might otherwise cause the contact strip 77 to move back out of contact with the flange 76 after making contact therewith. The plate 75 is provided with an opening 105 84 adjacent the gap 80 in the peripheral flange 76 and in the path of the contact strip 78 so that during a portion of the time while the strip 77 is in engagement with the insulating body 74 the contact strip 78 will be in engagement with the insulating body 74. 110

As shown in Fig. 9 of the drawing, the contact strip 79 is connected by means of a wire 85 to a suitable source of current, the contact strip 78 is connected by means of a wire 86 to the motor 49 and the contact strip 77 is connected by means of a wire 87 to the heater 11. The heater 11 and the motor 49 are connected to the opposite terminal of the source of current by means of wires 88 and 89. The motor 49 is also connected to the source of current through an independent connection 90 in which there is a manually operable switch 91. The heater 11 has a main coil 11^a and auxiliary coils 11^b and 11^c, the main coil 11^a being connected with the wires 87 and 88 as that when the circuit through the contact 77 is closed a circuit is established through this coil to generate sufficient heat for popping the corn. The auxiliary coils 11^b and 11^c 130

are connected in series with the main coil and an auxiliary circuit is provided through the wire 88, coils 11^a, 11^b, 11^c and to the negative line through a wire 88^a, a switch 11^d being provided for cutting the coil 11^c into or out of the auxiliary circuit. The auxiliary circuit is always closed while the machine is in operation and serves to keep the heater warm during the intervals during 10 which the main heater circuit is open. The switch 11^d serves to regulate the current through the auxiliary circuit and when opened increases the current through the auxiliary circuit as may be desirable to provide more heat for popping.

The contact strip 79 is always in engagement with the plate 75 and the contact strips 77 and 78 are in engagement with the flange 76 and the plate 75 except when passing over the gap 80 and the opening 84. If the switch 91 is closed the motor 49 will continue to operate regardless of whether the contact strip 78 is in engagement with the plate 75 or with the insulating body 74. 20 However, if the switch 91 is opened the motor circuit will be completed through the wire 85, contact strip 79, plate 75, contact strip 78 and wire 86 until the opening 84 moves into registry with the contact strip 78. 25 As above explained, the popping device moves through a complete cycle of operations during each revolution of the ratchet wheel 57. The controller disk 58 rotates with the ratchet wheel and the opening 84 in the plate 75 is so positioned that the circuit is broken through the contact strip 78 just after the unpopped corn has been discharged from the cylinder and just prior to the operation of the valve 39 to 30 feed a fresh charge of unpopped corn to the cylinder. It will thus be apparent therefore that whenever the manually operated switch 91 is turned on, the motor 49 will be energized and will continue to operate 35 as long as the switch 91 is closed. When a sufficient amount of corn has been popped the switch 91 will be opened but the opening of the switch 91 will not immediately stop the motor since the circuit through the motor will be completed through the contact strips 78 and 79 and this circuit will remain closed until the contact strip 78 engages the insulating body at the opening 84 causing the motor to continue its operation until 40 the popping cycle is completed. While the contact strip 77 is in engagement with the insulating body 74, the circuit through the heater will be broken. The gap 80 in the flange 75 is so positioned on the disk that the main circuit through the heater 11 is broken while the discharge gate 13 is being operated to discharge the unpopped corn from the cylinder 1 and while the valve 39 is being operated to deliver a charge of 45 unpopped corn to the cylinder. The open-

ing 84 is so disposed with respect to the gap 80 that the circuit through the motor 49 is always completed before the contact strip 77 engages the flange 75 at the rear end of the gap 80 to reestablish the circuit through 70 the heater 11 so that a momentary closing of the switch 91 cannot cause a slight movement of the disk which would complete the circuit through the heater before the motor circuit through the plate 75 is closed. Otherwise the motor might be stopped and the heater still remain on.

To operate the machine, the switch 91 is moved to closed position starting the motor 49 which continuously rotates the cylinder 1 through the gears 50, 51, 53 and 54 and intermittently turns the ratchet 57 and the controller disk 58 by means of the lever 59 which is engaged by the roller 60 on the gear 54 and carries the pawl 61 engaging 80 the ratchet wheel 57. Since the machine always stops in the same position with the roller 63 on the ratchet wheel 57 in position to engage the valve actuating bar 65, the valve 39 is immediately operated through 85 the connecting rod 48 which carries the arm 65. Immediately after the charge of unpopped corn has been delivered to the cylinder 1, the disk 58 is rotated sufficiently to bring the contact 77 into engagement with 90 the flange 76 to complete the main circuit through the electric heater 11. The actuating lever 59 will be adjusted to provide sufficient time for the revolution of the controller disk and ratchet wheel to permit the 95 corn which has been fed to the cylinder to be popped before the discharge gate 13 is operated to discharge the unpopped corn. The rate of revolution of the ratchet wheel 100 57 and disk 58 may be varied by adjusting the stop 63 to vary the throw of the lever 59. When the cam plug 72 comes into engagement with the conical disk 68 on the 105 slidable rod 67, the trip roller 70 will be moved toward the cylinder 1 into the path 110 of the end portion 30 of the discharge gate actuating lever 24 to shift the discharge gate 13 into engagement with the outer screen 8 of the cylinder. After the cylinder has turned substantially one-half of a revolution, the lug 31 on the inner side of the curved actuating lever 24 will engage with the fixed trip roller 73 carried by the frame 55 shifting the gate 13 back to its normal 115 position in which position the gate 13 will 120 discharge its contents into the discharge chute 21. At the same time that the cam lug 72 engages the disk 68, the gap 80 in the flange 76 will be brought beneath the contact strip 77 and the main circuit 125 through the electric heater 11 will be broken. After the gate 13 has been actuated to discharge the unpopped corn the roller 66 on the ratchet wheel 57 will again engage with the actuating bar 65 and oper- 130

ate the valve 39 to deliver a charge of unpopped corn to the cylinder.

The cycle of operations above described will be repeated as long as the switch 91 remains closed. When the switch 91 is opened the motor 49 will continue to operate until the circuit through the contact strip 78 is broken at the end of the popping cycle.

10 If it is desirable at any time to discharge the contents of the cylinder before the completion of the popping cycle the slideable rod 67 may be manually operated to trip the discharge gate 13. If it is desirable to stop 15 the entire machine before a cycle of operation is completed, the usual circuit breaking devices of the power circuit may be employed.

Having described my invention, I claim—

20 1. In a corn popping machine, a popping device having a definite cycle of operations for popping and delivering a charge of popped corn, means for driving said popping device, means operated by the driving means for delivering a charge of unpopped corn to the popping device at the beginning of each cycle of operations, a manually operable controlling device movable to on and off positions to cause the popping machine 25 to be driven or stopped, and an auxiliary controlling device operable when said manually operated controlling device has been moved to off position to continue the operation of the popping device until the end of 30 the cycle and to then render said driving means inoperative.

2. In a corn popping machine, a popping device having a definite cycle of operations for popping and delivering a charge of popped corn, means for driving said popping device, means operated by the driving means for delivering a charge of unpopped corn to the popping device at the beginning of each cycle of operations, a manually operable controlling device movable to on and off positions to cause the popping machine 45 to be driven or stopped, and an auxiliary controlling device operated by the driving means, an auxiliary device being operable 50 when the manually operated device has been moved to off position to render said driving means inoperative at the end of the cycle of the popping device.

3. In a corn popping machine, a popping 55 device having a definite cycle of operations for popping and delivering a charge of popped corn, means for driving said popping device, means operated by the driving means for delivering a charge of unpopped 60 corn to the popping device at the beginning of each cycle of operations, a controlling device operated by the driving means for rendering the same inoperative when the cycle of operations of the popping device 65 has been completed, and a manually oper-

able controlling member adapted when moved to one position to cause said driving means to operate said popping device and to render said first controlling device inoperative and when moved to another position to render said first controlling device operative.

4. In a corn popping machine, a popping device having a definite cycle of operations for popping and delivering a charge of popped corn, an electric motor for driving said popping device, means operated by the motor for delivering a charge of unpopped corn to the popping device at the beginning of each cycle of operations, a circuit breaking device operated by the motor for opening the motor circuit when the cycle of operations of the popping device has been completed, and a manually operable device for rendering said circuit breaking device 85 inoperative.

5. In a corn popping machine, a popping device having a definite cycle of operations for popping and delivering a charge of popped corn, an electric motor for driving said popping device, means operated by the motor for delivering a charge of unpopped corn to the popping device at the beginning of each cycle of operations, a motor circuit including a circuit breaking device operated by the motor adapted to open the motor circuit at the end of each cycle of operations of the popping device, and an auxiliary motor circuit including a manually operable switch.

6. In a corn popping machine, a popping device having a definite cycle of operations for popping and delivering a charge of popped corn, an electric motor for driving said popping device, said popping device having means for separating and discharging the popped corn during the popping operation, means for continuously driving said popping device, means for automatically delivering a charge of unpopped corn to the popping device at the beginning of each cycle of operations, means for automatically discharging the corn which remains unpopped at the end of each cycle of operations, means for automatically stopping the popping device after each discharge of unpopped corn from the popping device, and before the delivery of a fresh charge thereto, and manually operable means for rendering said automatic stopping means inoperative whereby said popping device may be continuously operated to pop successive charges of corn.

7. In a corn popping machine, a popping device having a definite cycle of operations for popping and delivering a charge of popped corn, means for continuously operating said popping device through a plurality of popping cycles, means for automatically feeding a charge of unpopped corn to

- the popping device at the beginning of each popping cycle, and means for varying the time interval between the actuations of the charge feeding device.
5. In a corn popping machine, a popping device having a definite cycle of operations for popping and delivering a charge of popped corn, means for continuously operating said popping device through a plurality of popping cycles, a reservoir for unpopped corn, a charge feeder for delivering charges of unpopped corn from the reservoir to the popping device, means driven from said driving means for actuating said charge feeder, and means for varying the rate of movement of said feeder actuating device.
9. In a corn popping machine, a popping cylinder having means for separating and discharging popped corn therefrom during the popping operation, means for continuously driving said cylinder, means for supplying charges of unpopped corn to the cylinder and for discharging unpopped corn from the cylinder, a rotating member driven from the driving means for controlling the actuation of said feeding and discharging means, and means for varying the rate of movement of said rotating member.
10. In a corn popping machine, a popping cylinder, means for continuously rotating the cylinder, means in said cylinder for separating popped corn from the unpopped corn and discharging the popped corn during the rotation of the cylinder, means carried by the cylinder for discharging unpopped corn therefrom, a feeder for delivering charges of unpopped corn to the cylinder, a rotating member driven by the cylinder driving means, means carried by the rotating member for actuating the feeder, a trip for actuating said discharger, and means carried by said rotating member for actuating said trip.
11. In a corn popping machine, a popping cylinder, means for continuously rotating the cylinder, means in said cylinder for separating popped corn from the unpopped corn and discharging the popped corn during the rotation of the cylinder, means for feeding charges of unpopped corn to the cylinder, means carried by the cylinder for discharging unpopped corn therefrom, a rotating member driven by the cylinder driving means, means for periodically operating the feeding means from the rotating member, means actuated by the rotating member for periodically operating the discharging means, and means for varying the rate of rotation of the rotating member.
12. In a popping machine, a continuously driven popping device, means operating at predetermined intervals to first discharge corn from the popping device and then to feed a fresh charge thereto, and means for adjusting said means to vary the time in- terval between successive operations of the feeder and discharger.
13. In a popping machine, a continuously driven popping device, a stationary heating device associated therewith, means operating at predetermined intervals to first discharge corn from the popping device and then to feed a fresh charge thereto, and means for automatically rendering said heating device inoperative during the operation of the feeding and discharging means.
14. In a popping machine, a continuously driven popping device, an electrical heating device associated therewith, means operating at predetermined intervals to first discharge corn from the popping device and then to feed a fresh charge thereto, and means for automatically interrupting the supply of current to the heating device during the operation of the discharging and feeding means.
15. In a popping machine, a continuously driven popping device, an electrical heating device associated therewith, means operating at predetermined intervals to first discharge corn from the popping device and then to feed a fresh charge of corn thereto, means for varying the time interval between successive operations of the discharging and feeding means, and means for interrupting the supply of current to the heating device during the operation of the discharging and feeding means.
16. In a popping machine, a popping device, means for continuously driving the popping device, a ratchet wheel, means for intermittently actuating the ratchet wheel from the driving means, means operated by the ratchet wheel upon each revolution thereof to feed a charge of corn to the popping device, and means for adjusting said ratchet wheel operating means to vary the rate of movement of the ratchet wheel.
17. In a popping machine, a popping device, means for continuously driving the popping device, a ratchet wheel, means operated by the driving means for imparting an intermittent rotation to the ratchet wheel, means operated by the ratchet wheel upon each revolution thereof for causing the popping device to be emptied and for feeding a fresh charge of corn thereto, an electric heater associated with the popping device, and means associated with the ratchet wheel for interrupting the supply of current to the heating device during the discharging and feeding operations.
18. In a popping machine, a popping cylinder, an electric motor for continuously rotating the cylinder, a rotating actuating and timing device operated by the motor, means controlled by said timing device for discharging corn from the cylinder and for feeding a fresh charge of corn thereto, an electric heater associated with the cylinder,

said heater and motor having circuits controlled by said timing device, said motor having an additional circuit controlled by a manually operated switch.

- 5 19. In a popping machine, a popping device, an electric motor for driving said device, a rotating member driven by said motor, means carried by said rotating member for controlling the discharge of unpopped 10 corn from the popping device, the feeding of corn thereto and the operation of the motor, and means for varying the rate of movement of the controlling member relative to the popping device.
- 15 20. In a popping machine, a popping device, an electric motor for driving said device, an electric heater associated with the popping device, a manually operated switch which when closed causes the motor to operate, means for emptying the popping device and for feeding a fresh charge thereto, an actuating and timing device actuated by the motor for causing the operation of the emptying and feeding means at definite intervals, said device having means for interrupting the flow of current to the heater during the emptying and feeding operations and for stopping the motor during the next 25 interval between the discharging and feeding operations after said manually operated switch has been moved to open position.
21. In a popping machine, a rotatably mounted popping cylinder having means for separating the popped from the unpopped 30 corn and discharging the popped corn during the popping operation and means for

discharging the unpopped corn, an electric heater associated therewith, an electric motor for rotating the cylinder, a rotatable member driven by the motor, means for varying the rate of movement of the rotatable member with respect to the cylinder, means for feeding a fresh charge of corn to the cylinder, means controlled by the rotatable member for actuating means for discharging unpopped corn from the cylinder and for feeding a fresh charge to the cylinder, for interrupting the flow of current to the heater during the discharging of unpopped corn from the cylinder and the feeding of a fresh charge thereto, and for stopping the motor in the interval between said discharging and feeding operations.

22. In a popping machine, a popping device, an electric heater associated therewith, an electric motor for driving the popping device, means for controlling said heater and motor comprising a rotating disk driven by said motor, said disk having a conducting portion permanently connected with a source of current, a contact member in the heater circuit engaging said disk, a contact member in the motor circuit engaging said disk, said disk having an insulating portion engageable with the contact members to cut off the supply of current to the heater and motor, and manually controlled means for supplying current to the motor independently of the disk.

In testimony whereof, I hereunto affix my 70 signature.

WILLIAM D. ROOT.
